(57) **CLAIM**

The ornamental design for a vacuum splint, as shown and described.

DESCRIPTION

FIG. 1 is a front view of the vacuum splint;

FIG. 2 is a left side view;

FIG. 3 is a back view; and,

FIG. 4 is a top view thereof.

The surface treatments consisting of small squares and broken hatched lines are understood to extend uniformly across the surfaces of which they are applied.

1 Claim, 2 Drawing Sheets

FIG. 2

FIG. 1
